UNITED STATES PATENT OFFICE.

WILLIAM F. BEVILL, OF FORDYCE, ARKANSAS.

AUTOMOBILE LOCK AND HOUSING THEREFOR.

Application filed August 31, 1923. Serial No. 660,378.

To all whom it may concern:

Be it known that I, WILLIAM F. BEVILL, of Fordyce, in the county of Dallas and State of Arkansas, a citizen of the United States, have invented certain new and useful Improvements in Automobile Locks and Housings Therefor, of which the following is a specification.

This invention relates to ignition switch locks of the type disclosed in an application filed by me November 1, 1922, Serial No. 598,347. In my said application I showed and described a mechanism in which a permutation lock controlled the admission of a circuit-closing key so that if the key were withdrawn and the combination upset the motor would be stopped and could not be started until the combination had been properly operated to permit the reinsertion 20 of the key. This mechanism was efficient and generally satisfactory but it sometimes happened that the operator would forget to break the combination after withdrawing the key so that any one could push in the 25 key and start the motor.

The primary object of my present invention, therefore, is to provide a locking mechanism in which, while the insertion of the key will close the ignition circuit, the 30 withdrawal of the key will not break the circuit and stop the motor but the motor will continue to run until the combination of the lock is broken. To again start the motor, the key must be pushed in and this 35 cannot be done until the lock has been set by one knowing the combination.

Another object of the invention is to provide a novel, compact and efficient means for securing the lock within a container or casing. Other objects will incidentally appear 40 in the course of the following description.

The invention is illustrated in the accompanying drawings, in which—

Fig. 1 is a side elevation of a casing housing my present improvements, a portion of the instrument board being shown in section,

Fig. 2 is an end elevation,

Fig. 3 is a longitudinal section showing 50 the circuit closed.

Fig. 3^a is a view similar to Fig. 3, showing the switch open.

Fig. 4 is a plan view of the lock casing with the container in horizontal section,

55 Figs. 5 and 6 are transverse sections, showing the active and released positions of the

devices for securing the lock case in the container.

Fig. 7 is a view partly in side elevation and partly in longitudinal section showing 60 the means for setting the securing devices shown in Figs. 5 and 6,

Fig. 8 is a detail elevation of the switch,

Figs. 9 and 10 are, respectively, edge and 65 face views of a double eccentric forming part of the mechanism shown in Fig. 7.

Figs. 11 to 18 are elevations of the tumblers.

In the drawings, the reference numeral 1 indicates a portion of the instrument board 70 of an automobile to which is secured the open end of a container or housing 2, a head 3 fitting snugly in the end of the container. The coil 4 is secured in the container in any convenient or preferred manner, and the 75 container is provided with an outlet 5 for the circuit wires 6.

Upon the end of the wall of the head 3 is secured a lock case 7, the inner or forward end of said case consisting of a plate 8 of 80 vulcanite, fiber or other non-conducting material. Spaced terminal posts 9 are secured in and extend through the plate 8 and, at the forward side of the plate, are equipped with terminal clips 10 in which the circuit 85 wires are engaged. At the rear side of the plate 8, within the lock case, the posts 9 carry contacts or switch members 11 which are in the form of overhanging resilient lips adapted to be engaged by a circuit-closing 90 switch member 12 as will presently more fully appear. At the center of the plate 8 is secured a bearing sleeve 13 in which is rotatably fitted a spindle 14 which extends through the lock case, the head 3, and the 95 instrument board, and is provided at its rear free end with a milled knob 15. A dial 16 is secured or produced upon the instrument board concentric with the spindle and a pointer or index finger 17 is secured upon the spindle to play over and cooperate with the dial.

A master tumbler 18 has its hub 19 secured upon the spindle with the ends of the hub abutting the sleeve 13 and the rear end 105 wall of the lock case, and a series of openings 20 is formed through the tumbler concentric with the hub, a head stud 21 being engaged in one of said openings determinate according to the combination selected for 110 the lock. A spring-pressed dog or click 22 is mounted upon the rear end wall or plate

of the lock case in position to engage the openings 20 as they successively align with the dog when the tumbler is rotated. The dog aids in holding the tumbler at rest, and the operator may follow the combination by counting the clicking sounds of the dog engaging the openings as well as by watching the digits or other characters upon the dial 16. Other tumblers 23, 24, 25, are rotatably fitted upon the sleeve 13 and each tumbler is provided with a circular series of openings 27 to receive studs 28 like the stud 21, the master tumbler, however, having a stud head upon its front face only while the other tumblers have stud heads upon both faces. Spacing washers 29 are fitted upon the bearing sleeve between the several tumblers and in front of the foremost tumbler, and a spring 30 is coiled around the sleeve between the foremost washer and the plate 8, the tumblers being thus maintained in such relation that the stud heads may easily engage when the combination is operated and the tumblers may yield slightly to avoid jamming when an attempt is made to push in the key or switch before the combination is set. A stop pin or lug 31 projects from the plate 8 into the path of the stud head 32 on the front face of the innermost tumbler 25 to arrest the movement of the tumbler at the proper point when the combination is to be broken or worked, and each tumbler is provided with an opening 33 which is at the same radial distance from the bearing sleeve as the opening 34 through the plate 8. When the combination has been properly set the opening 34 and the openings 33 will be in alignment and the circuit key or pin 35 may be inserted. When the combination is broken, the openings will be out of alignment, and alignment thereof to permit insertion of the key or pin cannot be effected unless the combination be known.

The key or pin 35 is slidably fitted through a sleeve 36 which has threaded engagement within a thimble 37 which is secured in the instrument board and the end of the lock case. Inward movement of the pin is limited by impact of a flange or shoulder 38 thereon with the end of the sleeve 36 and outward movement is limited by the head 39 impinging against the inner end of the sleeve. The said head is tapered so that it may readily engage in the opening 34, which opening is lined with a metal bushing 40 to prevent wear upon the vulcanite plate, and the lower side of the bushing is extended to provide a positive guide and support for the head 39. The switch plate or circuit-closing member 12 is a block or plate of vulcanite or fiber bearing against the plate 8 and slidably held thereto by the spring 30 bearing against a washer 41 fitted upon the sleeve 13 in contact with the switch plate. The switch plate is constructed with a cen-

tral slot 42 through which the sleeve 13 and the stop pin 31 pass and which permits the sliding movement of the plate. Across the upper end of the plate and bridging the upper end of the slot 42 is secured a contact 70 plate 43 which engages closely under the contact lips 11, when the plate is raised and thereby closes the ignition circuit, as will be understood upon reference to Fig. 8. At the lower end of the switch plate is secured a wear or striker plate 44 having a horizontal flange 45 along its upper edge and provided at its lower edge with a central depending tongue 46 which is inclined toward the plate 8 and, in the lower position of the switch plate, projects into the bore of the bushing 40 and in the path of the circuit-closing key or pin 35. When the switch plate is in its raised position, the flange 45 crosses the orbit of the stud head 32 on the tumbler 25 so that, if the tumbler be rotated, said stud head will be caused to ride on said flange and thereby effect downward movement of the switch plate.

Assuming the motor to be at rest, the pin or key 35 will have been drawn out, the combination broken, and the switch plate lowered. When the motor is to be started, the spindle 14 is manipulated in accordance with the combination for which the tumblers have been arranged so that the openings 33 will be brought into alignment, whereupon the pin 35 is pushed in so that the head 39 enters the opening 34. As the head 39 enters the opening 34, it will impinge against the inclined tongue 46 and, consequently, exert a lifting force upon the switch plate which will raise the latter and carry the contact plate 43 under and into close frictional engagement with the lips 11 to close the circuit which will permit the motor to operate. When the motor is to be stopped, the pin 35 is first drawn out to the full extent of its movement but this act does not break the 110 circuit inasmuch as the frictional engagement between the switch plate and the adjacent parts is sufficient to hold it in its raised position. To lower the switch plate, the spindle 14 must be manipulated so that the tumbler 25 will be rotated and the stud 32 caused to ride upon the flange 45, as above stated. This action breaks the combination, and the pin cannot then be again pushed in until after the tumblers have 120 been properly set by one knowing the combination.

At diametrically opposite points of the head or closure 3 I secure, by hinges 47, the locking arms or levers 48 which extend longitudinally of the closure and project through the open end of the same. At the free ends of these arms are lugs 49 which are adapted to engage behind a rib or flange 50 on the housing or container where- 130

by to lock the closure in place. It will be noted that the arms are entirely within the container so that tampering therewith is prevented, and also that the closure abuts the rib so that the accurate placing of the closure with its outer end flush with the end edges of the container is assured. A metal reinforcing plate 51 is secured upon the lower portion of the end plate 8 of the lock case and a bracket plate 52 is secured upon the plate 51, a hub 53 being journalled in and extending between the plates 51 and 52 in alinement with the opening 34 in the plate 8. This hub 53 has an angular bore 54 and carries oppositely extending eccentrics 55, one of which is provided with a lateral pin or lug 56 adapted to play in a slot 57 in the plate 51 concentric with the hub and limit the movement of the hub and the eccentrics by engaging the ends of the slot. Each eccentric 55 fits within a circular opening provided therefor in the shorter arm of an angle lever 58, the levers being held upon the eccentrics by the plates 51 and 52, and the longer arms of the levers extending in opposite directions and terminating in T-heads 49 which have their stems engaged in longitudinal slots 60 in the locking arms 48. It will be readily understood that if the longer radii of the eccentrics be turned in one direction, the angle levers will swing the arms 48 so as to carry the lugs 49 into engagement with the rib 50, while if said radii be turned in the opposite direction the lugs will be withdrawn to permit removal of the closure. To effect movement of the angle levers, I provide the key 61 which has an angular end 62 adapted to engage in the angular bore 54 of the hub 53. To permit the use of the key 61, the sleeve or ferrule 36 is withdrawn from the thimble 37 after which the key 61 is inserted, as shown in Fig. 7.

Having thus fully described my invention, what I claim as new and desire to secure by Letters Patent of the United States is:—

1. In apparatus for the purpose set forth, the combination of a circuit-closer, an element insertible to close the circuit-closer and withdrawable without opening the same, and means to permit or prevent the insertion of said element, said means acting to open the circuit-closer when set to prevent the insertion of said element.
2. In apparatus for the purpose set forth, the combination of spaced electric contacts, a switch plate arranged to engage said contacts and close a circuit through the same, means for moving the switch plate to active position only, and means to permit or prevent the application of the first-mentioned means, said last-mentioned means moving the switch plate to inactive position

when being set to prevent application of 65 the first-mentioned means.

3. In apparatus for the purpose set forth, the combination of an electric switch, a key for closing the switch, and a permutation mechanism to permit or prevent the insertion of the key, said mechanism including 70 an element operable to open the switch when the key is withdrawn.

4. In apparatus for the purpose set forth, the combination of spaced electrical contacts, a slidably mounted switch plate adapted to engage and close a circuit through the contacts, a key adapted to raise the switch plate into circuit-closing position, means for frictionally holding the 75 switch plate in raised position, and means to lower the switch plate, said means being operable to prevent or permit the insertion of the key.

5. In apparatus for the purpose set forth, the combination of spaced electrical contacts, a slidably mounted switch plate adapted to engage and close a circuit through the contacts, a key adapted to raise the switch plate into circuit-closing position, means for frictionally holding the switch plate in raised position, and a permutation mechanism to prevent or permit the insertion of the key, said means including a tumbler arranged to lower the switch plate when the key is withdrawn. 85 90 95

6. In an apparatus for the purpose set forth, the combination of spaced contacts, a switch plate mounted below said contacts for vertical sliding movement; a key insertible below the switch plate to raise the same into engagement with the spaced contacts, and a permutation mechanism to prevent or permit the insertion of the key and including a tumbler arranged adjacent the switch plate and adapted to lower the same when the key is withdrawn. 100 105

7. In an apparatus for the purpose set forth, the combination of spaced electrical contacts, a vertically slidable switch plate 110 adapted at its upper end to engage said contacts and close a circuit therethrough, a flange extending across the switch plate below its upper end, an inclined tongue depending from the lower end of the 115 switch plate, a key movable against said tongue whereby to raise the switch plate into engagement with the spaced contacts, and a tumbler adapted in one position to permit operation of the key and in another position to prevent use of the key, said tumbler being provided with a stud to ride on said flange and lower the switch plate as the tumbler moves into position to prevent use of the key. 120 125

In testimony whereof I hereunto affix my signature.

WILLIAM F. BEVILL.
